UNITED STATES PATENT OFFICE.

FRANK D. HERRING, OF CUERO, TEXAS, ASSIGNOR OF ONE-HALF TO JOHN W. HERRING,
OF CUERO, TEXAS.

THREAD CUTTER.

Application filed February 6, 1920. Serial No. 356,709.

To all whom it may concern:

Be it known that I, FRANK D. HERRING, a citizen of the United States, residing at Cuero, in the county of De Witt and State 5 of Texas, have invented new and useful Thread Cutters, of which the following is a specification.

This invention relates to new and useful improvements in thread cutting devices, and 10 more particularly to a thread cutting device for attachment to automatic looms.

The primary object of the invention is to provide a thread cutting device disposed in such relation to the cloth passing through 15 the machine, that the cutter proper will operate along the selvage of the cloth to trim the extending ends of the threads forming the cloth.

A further object of the invention is to 20 provide a device of this character wherein the cutting blades thereof will be automatically adjusted with relation to each other to compensate for wear between the cutting blades to cause the cutting blades to properly perform the cutting operation.

A still further object of the invention is to 25 provide a cutting attachment which will be operated by the movement of the cloth through the machine, thus eliminating the necessity of providing auxiliary operating 30 mechanism for controlling the cutting blades.

With the foregoing and other objects in view which will appear as the description 35 proceeds, the invention resides in the combination and arrangement of parts and in the details of construction hereinafter described and claimed, it being understood that changes in the precise embodiment of 40 the invention herein disclosed, may be made within the scope of what is claimed, without departing from the spirit of the invention.

Referring to the drawing:—

Figure 1 illustrates a plan view of the 45 cutting device constructed in accordance with the present invention.

Figure 2 illustrates a longitudinal sectional view taken on line 2—2 of Figure 1.

Figure 3 illustrates a transverse sectional 50 view taken on line 3—3 of Figure 2.

Referring to the drawing in detail, the reference character 5 designates the frame of the cutting device, which is provided with 55 an upwardly extending portion 6, provid-

ing a bracket whereby the frame and cutting device carried thereby may be supported in proper relation on a loom.

This frame 5 is curved transversely of its length as at 7, to provide a clearance for 60 the operating roller 8 disposed to operate within the frame, and as shown, the opposed ends of the frame 5 extend upwardly to provide seats for the bearing members 9 and 10, on which the operating roller 8 is 65 supported.

One end of the frame 5 is cut away as at 11 to accommodate the depending portion 12 of the removable portion 18 of the bracket member to permit the cutting device to be readily and easily removed from the loom to which the same is attached in the event that it becomes necessary to resharpen or replace the cutting blades 70 thereof.

Supported adjacent the depending portion 12, is a stationary cutting blade 14, which cutting blade 14 is slotted as at 15 to embrace the bearing 10, the upper wall of the slotted portion 15 being beveled as 80 at 16 to provide a cutting surface, which cutting surface cooperates with the rotary cutting blade 17 which cutting blade is provided with a beveled edge 18' notched throughout its periphery, the notches being 85 arranged in spaced relation with each other to grasp the threads forming the selvage to bring the same into proper cutting relation with the cutting edges.

Extending from one of the end walls of 90 the rotary roller 8, are the pins 19, which pins are seated in suitable openings formed in the end of the operating roller 8, and extend into openings of the blade 17, to connect the rotary cutting blade 17 and operating roller 8, so that movement of the operating roller 8, will result in a relative movement of the rotary cutting blade 17.

Surrounding the bearing 10 and disposed 95 between one end of the frame and the stationary cutting blade 14 is a coiled spring 20 adapted to exert a pressure on the stationary cutting blade 14 to urge the same towards the rotary cutting blade 17, thus insuring the stationary cutting blade 14 105 being maintained in proper relation with the rotary cutting blade 17.

The operating roller 8 is provided with a plurality of pins extending from the periphery thereof, the pins being disposed in 110

spaced relation throughout the entire outer surface of the roller 8 and as shown, the pins extend in a direction towards the rotary cutting blade 17 so that the pins will direct the cloth laterally in its passage through the loom, to bring the selvage thereof into a position between the rotary cutting blade 17 and the beveled edge 16 of the stationary cutting blade 14.

10 In the operation of the device, as before stated, the cutting device is properly positioned on the frame of the loom so that the cutting blades thereof will operate in a plane with the selvage of the cloth passing through the loom. It follows that the cloth passing over the operating roller 8, due to its contact with the pins 21, causes the roller 8 to revolve with the result that the rotary cutting blade 17 supported at one end of the roller revolves to accomplish the cutting result.

Having thus described the invention, what I claim as new is:—

In a device of the class described, a frame,

a roller rotatably mounted within the frame 25 and having openings disposed in one end thereof, a stationary member having a cut out portion extending from one edge thereof, one of the walls of the cut out portion being beveled to provide a cutting edge, a 30 rotary cutting member, having pins adapted to be positioned in the openings of the roller, to removably secure the rotary cutting member to the roller, said rotary cutting member having a plurality of notches adapted 35 to pick up the threads of the selvage of cloth and carry the threads to the stationary cutting blades, and means for normally urging the stationary cutting blades into close engagement with the rotary cutting blades. 40

In testimony that I claim the foregoing as my own, I have hereto affixed my signature in the presence of two witnesses.

FRANK D. HERRING.
